UNITED STATES PATENT OFFICE.

WILLIAM BOWMAN, OF MILL GROVE, MICHIGAN.

FENCE-POST.

SPECIFICATION forming part of Letters Patent No. 603,166, dated April 26, 1898.

Application filed November 26, 1897. Serial No. 659,897. (No model.)

To all whom it may concern:

Be it known that I, WILLIAM BOWMAN, a citizen of the United States, residing at Mill Grove, in the county of Allegan and State of Michigan, have invented certain new and useful Improvements in Fence-Posts; and I do hereby declare the following to be a full, clear, and exact description of the invention, such as will enable others skilled in the art to which it appertains to make and use the same.

This invention relates to fence-posts; and it consists of the construction and arrangement of the several parts, which will be more fully hereinafter described and claimed.

The object of the invention is to provide a fence-post having an indestructible base and an attachment whereby wooden pieces may be secured to and extend above the surface of the ground and which may have substituted therefor similar pieces in the event of breakage, decay, or rotting of the same.

In the accompanying drawings, Figure 1 is a perspective view showing the fence-post in operative position. Fig. 2 is a transverse vertical section through the device shown by Fig. 1. Fig. 3 is a plan of a part of the device.

Referring to the drawings, wherein similar numerals of reference are employed to indicate corresponding parts in the several views, the numeral 1 designates a cast-metal base of suitable length and dimensions and adapted to be preferably made hollow, though a departure from the spirit of the invention would not exist if the same were made solid. At the upper portion of one side of the base a wrought-metal socket 2 is secured and has openings extending therethrough and through the adjacent portion of the said base and is adapted to receive the lower end of a wooden post 3 and be held in connection therewith by means of bolts or other fastenings 4. The wooden post is removable and may at any time be replaced by another of a similar nature when found necessary, and the socket is sufficiently long to provide a rigid support for the lower end of the wooden post. In setting up the

device the base 1 is embedded in the ground in a vertical position, together with the socket, if desired, or the said socket may with a portion of the base extend above the ground, this being regulated in accordance with the position of the post and the requirements of the person using the device. The wooden post of course is intended to be held above-ground, and the base is made angular in cross-section, so as to prevent the same from turning, and when made hollow, to give the same sufficient weight to sustain a stable position thereof, it can receive a filling of suitable material, such as dirt, sand, or the like.

The base 1 can be easily set up in operative position, and as an additional safeguard it could be coated with a paint or covering of such nature as to prevent corrosion. By making the socket of wrought metal a greater strain will be resisted thereby.

Many advantages will become apparent to those using the device, and it is obviously apparent that many minor changes in the details of construction and arrangement of the several parts may be made and substituted for those shown and described without in the least departing from the nature or spirit of the invention.

Having thus described the invention, what is claimed as new is—

A fence-post comprising a base having an independent socket on one side of the upper portion thereof, the said base being of cast metal and the socket of wrought metal, a post removably fitted in said socket, and bolts passed through the socket-post and the adjacent wall of the base and holding the several parts in removable relative position to each other, the said base being hollow and adapted to be filled with suitable weighting material, substantially as described.

In testimony whereof I affix my signature in presence of two witnesses.

WILLIAM BOWMAN.
